C. ERICKSON, JR

DEVICE FOR BABBITTING CONNECTING RODS

Filed March 18, 1922

UNITED STATES PATENT OFFICE.

CHARLES ERICKSON, JR., OF SCOTIA, CALIFORNIA.

DEVICE FOR BABBITTING CONNECTING RODS.

Application filed March 18, 1922. Serial No. 544,853.

To all whom it may concern:

Be it known that I, CHARLES ERICKSON, Jr., a citizen of the United States, residing at Scotia, in the county of Humboldt and State of California, have invented certain new and useful Improvements in Devices for Babbitting Connecting Rods, of which the following is a specification, reference being had to the accompanying drawings.

10 It is the purpose of the present invention to provide an improved mandrel, which is simple, efficient and practical in construction, for babbitting connecting rods, which are used on internal combustion engines.

15 The ends of connecting rods, which connect with the pistons in the cylinders of internal combustion engines are subject to considerable wear, and in order to take up this wear it is necessary to provide a lining on 20 the interior of the ends of the rods which connect with the pins of the pistons, in order to insure easy movements of the connecting rods.

25 Heretofore there have been devices employed, for babbitting the connecting rods, but such devices are more or less complicated in construction, therefore another purpose is to provide a simple construction, which not only insures a better lining, but 30 also holds the connecting rods firmer, and also permits the babbitt lining to be constructed more uniform, so as to insure easier and better movements of the rods, when in use.

35 Still another purpose is the provision of simple means for holding the rod in position, and the end of the rod which is to be provided with a babbitt bearing concentric with a supporting pin, while it is receiving 40 its babbitt lining.

Furthermore it is the aim to provide means for clamping the rod on the mandrel while it is being supplied with its babbitt bearing.

45 While the design and construction at present illustrated and set forth are deemed preferable, it is obvious that as a result of a reduction of the invention to a more practical form for commercial purposes, the invention may be susceptible of changes, and the 50 right to these changes is claimed, provided they are comprehended within the scope of what is claimed.

The invention comprises further features and combination of parts, as will be here-

inafter set forth, shown in the drawings and 55 claimed.

In the drawings:—

Figure 1 is a longitudinal sectional view through the improved mandrel or device for babbitting connecting rods, showing a connecting rod in position, ready to receive its babbitt lining;

Figure 2 is a plan view;

Figure 3 is a cross sectional view on line 3—3 of Figure 2;

Figure 4 is a cross sectional view on line 4—4 of Figure 2;

Figure 5 is a sectional view on line 5—5 of Figure 1;

Figure 6 is a sectional view through a 70 larger connecting rod head showing a bushing mounted on the pin 8 to take the excessive or increased size of head.

Referring to the drawings, 1 and 2 designate the base members of the mandrel, 75 which may be constructed in any suitable manner, and of any suitable material preferably cast iron. These base members may also be any suitable shape, preferably as illustrated, and secured in the base member 1 by means of the tapered pins 3 are rods 4, which connect the two base members. The rods 4 where they engage longitudinally through the base 1 are entirely cylindrical, as shown, but the remaining portions of said 80 rods, from one end of the base member 1 are flattened as shown at 5. The base member 2 is provided with longitudinally extending bores or openings 6, which, in cross section are shaped correspondingly to the rods 4. 85 Suitable thumb screws 7 are threaded through the base member 2, so that their shanks will frictionally engage with the flattened surfaces 5 of the rods 4, so as to hold the base member 2 in different adjusted 90 positions on the rods, according to the length of connecting rod to be supplied with a babbitt bearing. The rods 4 are milled to provide the flattened surfaces, so that the rods will not be marred or disfigured by the 95 shanks of the thumb screws 7 when tightened.

100 Pressed or shrunk, or otherwise fastened in the base 1 and centrally thereof is a pin 8, which passes through the bore 9 of the head 10 of a connecting rod 11, to be supplied with a babbitt bearing or lining. In fact the bore 9 of the head 10 of the connecting 105

rod is larger in diameter than the diameter of the pin 8, so that when the pin 8 is inserted through the head, a space is left between the surface of the pin and the surface 5 of the bore.

A collar 12 is first fitted upon the pin 8 before applying the head 10 of the connecting rod 11 to the pin. This collar 12 closely fits the base of the pin 8, and upon its upper 10 face is provided with an annular groove 13. When the collar 12 is applied to the pin, the groove registers with the space between the surface of the pin and the surface of the bore 9, so that when the Babbitt metal enters the space, it will flow into the groove, and cause to be formed an overlapping end 15 on the babbitt bushing or bearing, to prevent movement of the bearing in one direction, when the same hardens.

20 A second collar 14 is fitted closely to the upper end portion of the pin 8, and its under face is provided with an annular groove 15, which registers with the space between the pin and the bore 9, and per- 25 forms the same function as the groove 13. This collar 14 is provided with a pair of openings 16, through either one of which the Babbitt metal may be poured, so that it may enter the space between the pin 8 and 30 the bore 9. An additional collar 17 is also closely fitted to the upper extremity of the pin 8, and is secured thereto by a set bolt 18. In fact the set bolt 18 is ar- 35 ranged so that its extremity 19 partly pierces the pin 8, to insure holding the collar 17 in position. A pair of set bolts or screws 20 is threaded through the collar 17 perpendicularly, so as to bear upon the collar 14, thereby forcing the collar 14 toward the 40 head 10 of the connecting rod, which in turn is forced against the collar 12, in turn holding the collar tight against the upper face of the base 1, thereby preventing any leakage between the parts.

45 It will be noted that in babbitting the head 10 of the connecting rod, the head is engaged upon the pin 8 subsequently to applying the collar 12. The head is then ar- 50 ranged so that it is exactly concentric with the collar 12, then the collar 14 is applied, and the parts are clamped in position. The collar 17 has diametrically opposite apertures 21, which register with the apertures 16, so as to permit the Babbitt metal to be 55 poured thereinto. After the parts are thus arranged, the Babbitt metal is poured through the apertures 21, and then passes through the apertures or openings 16, into the groove of the upper collar, then in the 60 space between the pin 8 and the bore 9, and then into the groove 13. After the metal hardens, the head 10 can be detached from the pin 8, thereby leaving a babbitt lining or bearing constructed within the head, the 65 ends of the babbitt bearing overlapping the

ends of the head, thereby holding the bearing in place.

The base 2 is provided with an opening 22, which is substantially triangular in shape, and engaged with the crotch 23 of 70 the opening is a pin 24, which assumes a perpendicular position. In fact the opening 22 is designed to receive various sizes of wrist pins, such as 24, which receives the other end of the connecting rod. In fact 75 by means of the wrist pin 24, the head of the connecting rod is positioned to assume a position concentric with the collar 12. In other words the wrist pin 24 insures centering the head 10, by adjusting the base 2 80 on the mandrel rods 4. An elongated set bolt 25 is threaded through one end of the base 2, until its end protrudes into the opening 22. The screw 25 terminates in a bearing end 26, which bears upon the wrist pin, 85 to hold the same securely in the crotch of the opening 22, in order to insure holding the wrist pin rigid.

In order to separate the Babbitt metal (which constitutes the bearing for the connecting rod head) shims 27 preferably made of brass (though may be constructed of cardboard, paper or other material) are arranged between the two halves of the connecting rod head in such wise as to engage 90 with the pin 8 or bushing 28 in Figure 6. The bolts which fasten the two halves of the head together pass through the shims.

In Figure 6 there is illustrated a larger connecting rod head, and in order to fill 100 up excessive or increased size of the head a suitable bushing 28 is fitted on the pin 8, and between which and the interior of the head the Babbitt metal enters. Any num- 105 ber of bushings of this character may be em- ployed, that is to say, one at a time, so that various sizes of connecting rod heads may be babbitted.

The invention having been set forth, what 110 is claimed is:—

1. In a mandrel for babbitting connecting rods, a base provided with an upstanding pin passing through and spaced from the head of the connecting rod, collars fitted upon the pin and in contact with the op- 115 posite ends of the head of the connecting rod and provided with annular grooves upon their adjacent faces registering with the space between the pin and the bore of the head, and an additional collar secured upon the extremity of the pin, and means pass- 120 ing through the additional collar and bearing upon an adjacent collar, to jam the parts securely together, the additional col- 125 lar and the collar adjacent thereto having filling openings communicating with the space between the pin and the bore of the head, whereby Babbitt metal may be poured thereinto.

2. In a mandrel for babbitting connecting 130

rods, a base provided with an upstanding pin passing through and spaced from the head of the connecting rod, collars fitted upon the pin and in contact with the opposite ends of the head of the connecting rod and provided with annular grooves upon their adjacent faces registering with the space between the pin and the bore of the head, and an additional collar secured upon the extremity of the pin, and means passing through the additional collar and bearing upon an adjacent collar, to jam the parts securely together, the additional collar and the collar adjacent thereto having filling openings communicating with the space between the pin and the bore of the head, whereby Babbitt metal may be poured thereinto, and means carried by the base and connected to the other end of the connecting rod to insure centering the head of the connecting rod on said pin. 15 20

In testimony whereof I hereunto affix my signature.

CHARLES ERICKSON, JR.
